UNITED STATES PATENT OFFICE.

CECIL L. BOTHWELL AND KIRTLAND C. BARTON, OF EAST ST. LOUIS, ILLINOIS.

LINT FLUE.

Application filed March 28, 1927. Serial No. 178,923.

This invention relates to lint feed flues for conducting lint from linters, and an object of the invention is to provide such a flue with means for discharging the heavier foreign substances therefrom while the lint passes on through the flue.

Another object of the invention is to provide a lint feed flue for conducting lint from a linter, comprising an inclined straight, or approximately straight, receiving portion having a discharge slot across its lower portion through which the relatively heavy foreign substances that become detached and separated from the lint may pass to the outside leaving the relatively clean lint free to pass on through the flue. This receiving portion of the flue is tapered and approximately rectangular in cross section, thus preventing whirling movements of the air and the lint being drawn through the flue, with the result that the lint is prevented from being compacted into masses.

Other objects will appear from the following description, reference being made to the drawing in which

Fig. 1 is a side edge elevation, with parts in section, of our improved flue.

Fig. 2 is a side elevation showing a pair of flues in a relationship in which they are preferably assembled in connection with a linter.

Fig. 3 is a sectional view showing the means by which the parts at the lower end of the flues are held in spaced relationship to provide a discharge slot for the heavier particles.

From the linter a metallic wall 1 inclines upwardly and outwardly and has its upper edge extending into the lower end of the inclined flue receiving portion 2 overlapping the lower wall 3 of said receiving portion of the flue.

The wall 1 is spaced from the wall 3 of the receiving portion of the flue providing a discharge slot or chute 4. The walls 1 and 3 are held in this spaced relationship by interposed clips 5, preferably located near the side walls of the flue so as to reduce as far as possible the obstruction formed thereby,

leaving a free discharge outlet for the heavier separated materials.

It will be noted that the receiving portion of the flue extends in a nearly straight inclined direction and is approximately rectangular in cross section, although it tapers upwardly to connection with the flue proper 6.

By use of this invention the heavier foreign substances are permitted to separate from the relatively lighter lint fibers and drop out of the apparatus, while the lint fibers pass on through the flue, being prevented from matting and felting by the straight inclined flue structure. This straight inclined flue structure also permits the separation of the foreign matter as described.

The construction may be varied within equivalent limits without departure from the nature and principle of the invention. We do not restrict ourselves unnecessarily, but what we claim and desire to secure by Letters Patent is:—

1. A lint feed flue receiving portion approximately rectangular in cross section and composed of approximately straight inclined walls forming an upwardly tapering flue passage, and having a discharge opening for heavy particles near its end of greatest width.

2. An inclined lint feed flue having its lower end wider than its upper end and constituting a receiving end attached to a linter and provided with a discharge slot adjacent to the linter through which heavier particles may pass, while the lint continues to pass through the flue.

3. A lint feed flue having its receiving end attached to a linter and provided with a discharge slot adjacent to the linter through which heavier particles may pass, while the lint continues to pass through the flue, said flue being approximately rectangular in cross section and composed of approximately straight inclined walls forming an upwardly tapered passage.

4. The combination with an upwardly inclined wall of a linter, of an inclined lint

feed flue having its lower end enclosing said wall and forming therewith a downwardly inclined opening.

5. The combination with a linter having an upwardly inclined wall, of an upwardly inclined lint feed flue receiving portion approximately rectangular in cross section and

comprising approximately straight inclined walls forming an upwardly tapering passage enclosing the outer edge of said first named wall and forming therewith a discharge opening below said first named wall.

CECIL L. BOTHWELL.

KIRTLAND C. BARTON. *
